UNITED STATES PATENT OFFICE.

CHARLES SWANN, OF GRAVESEND, ENGLAND, ASSIGNOR OF ONE-THIRD TO CHARLES F. TOWNSEND AND ONE-THIRD TO SYDNEY ELLIOTT PAGE, BOTH OF LONDON, ENGLAND.

VACUUM CLEANING APPARATUS.

1,078,469.

Specification of Letters Patent.

Patented Nov. 11, 1913.

Application filed April 22, 1912. Serial No. 692,248.

To all whom it may concern:

Be it known that I, CHARLES SWANN, a subject of the King of Great Britain, residing at Gravesend, in the county of Kent, England, have invented certain new and useful Improvements in Vacuum Cleaning Apparatus, of which the following is a specification.

This invention relates to vacuum cleaning apparatus of the class in which the suction is produced by pumping water and has for its object to improve the efficiency of the suction and always to pump pure water.

According to this invention the suction efficiency is improved by pumping the water through a disk from which portions are removed and at the center of which is a cone.

The periphery of the cone may, in order to still further divide up the passing water, 20 be formed with cuts or projections which are splayed outwardly.

Figure 1 is a diagram showing the apparatus as a whole. Fig. 2 is a front elevation of the water distributing disk and cone and 25 Fig. 3 is a section of the same. Fig. 4 is a sectional view taken on line 2—2 of Fig. 1, showing the location of the distributing nozzle.

In Fig. 1, 1 is a pump pumping water 30 from the bottom of the tank 2 through a pipe 3 to the top of the same through a pipe 4 past an orifice and thus producing a suction in the pipe 5.

In Figs. 2 and 3, *d* is a disk cut away at 35 *e* and *f* is a cone provided with outwardly splayed cuts *f*'.

The assemblage is placed within the pipe 4 near to the orifice at which the suction is produced and serves in an improved manner to divide the water into streams.

The form of the conical attachment *f* is a

double truncated cone having its larger diameter at the center and of such a size that its larger diameter comes approximately opposite the middle of the openings in the disk 45 *d*. This larger diameter is provided with projections *f*' for the purpose of further breaking up the stream passing through the restricted openings *e*, *e*. It is found by this means that almost a complete vacuum can 50 be obtained in the pipe 5 connected to the suction nozzle.

What I claim as my invention and desire to secure by Letters Patent is:—

1. The combination in an ejector for suction producing apparatus, of a pipe having a passage adjacent to a suction nozzle, with a disk provided with a series of openings around its central area, and a truncated conical attachment having an expanding followed by a contracting surface extending into the said passage so as to interpose its 60 expanding surface opposite and immediately adjoining the disk openings, substantially as set forth.

2. In an injector for suction producing apparatus, the combination of a pipe having a passage adjacent to a suction nozzle, with a disk in the said passage provided with a series of segmental openings around 70 its central area, a conical surface attached thereto of double truncated character, and splayed projections at intervals on the larger diameter of the conical surface located opposite the disk openings, substantially as 75 and for the purpose set forth.

In testimony whereof I have affixed my signature in presence of two witnesses.

CHARLES SWANN.
